UNITED STATES PATENT OFFICE

WALTON W. TRIGG, OF CINCINNATI, OHIO

DESIGN FOR A SMOKER'S DEVICE

Application filed August 16, 1932. Serial No. 44,620. Term of patent 3½ years.

To all whom it may concern:

Be it known that I, WALTON W. TRIGG, a citizen of the United States, residing at Cincinnati, in the county of Hamilton and State of Ohio, have invented a new, original, and ornamental Design for Smoker's Device, of which the following is a specification, reference being had to the accompanying drawing, forming part thereof in which:

The figure is a perspective view of the smoker's device showing my new, original and ornamental design.

I claim:

The ornamental design for a smoker's device substantially as shown.

WALTON W. TRIGG.
